[57] **CLAIM**

The ornamental design for a cleaning apparatus for automotive engine parts and the like, as shown and described.

DESCRIPTION

FIG. 1 is a perspective view of the cleaning apparatus for automotive engine parts and the like in accordance with my new design;

FIG. 2 is a perspective view similar to FIG. 1 but with the door in an open position;

FIG. 3 is a left side elevation thereof;

FIG. 4 is a rear view thereof;

FIG. 5 is a top view thereof; and

FIG. 6 is a side elevation taken from the other side of FIG. 3.
